UNITED STATES PATENT OFFICE.

ROBERT A. MOORE, OF NEW YORK, N. Y., ASIGNOR TO SURE LOCK CORPORATION, OF NEW YORK, N. Y., A CORPORATION OF DELAWARE.

CURTAIN BUTTON.

Application filed June 25, 1923. Serial No. 647,454.

To all whom it may concern:

Be it known that I, ROBERT A. MOORE, a citizen of the United States, residing at New York city, borough of Manhattan, in 5 the county of New York and State of New York, have invented certain new and useful Improvements in Curtain Buttons, of which the following is a specification.

This invention relates to the general class 10 of separable fasteners and has particular reference to fasteners or buttons such as are used extensively for carriage or automobile curtains or the like.

Among the objects of the invention is to 15 improve the construction of this class of buttons with respect to neatness of appearance, ease and reliability of operation, strength and durability in service, and other features and advantages that will be appreciated as the device becomes better known and understood.

With the foregoing and other objects in view the invention consists in the arrangement and combination of parts hereinafter 20 described and claimed, and while the invention is not restricted to the exact details of construction disclosed or suggested herein, still for the purpose of illustrating a practical embodiment thereof reference is had 25 to the accompanying drawings, in which like reference characters designate the same parts in the several views, and in which—

Figure 1 is a substantially central sectional view of the device complete and in 30 locked position as on the line 1—1 of Fig. 3.

Fig. 2 is a sectional view of the same on the line 2—2 of Fig. 1, or at right angles to Fig. 1.

Figs. 3 and 4 are horizontal sections on 35 the corresponding lines of Fig. 1.

Fig. 4^a is a detail perspective view of the locking member in the form just referred to.

Fig. 5 is a view similar in character to Fig. 1, but indicating a modification.

Fig. 6 is a view of the same modification on the line 6—6 of Fig. 5.

Fig. 7 is a horizontal section on the line 7—7 of Fig. 5, but indicating the locking member in changed positions.

Referring now more specifically to the drawings I represent a stud or head member 10 of any suitable design or construction, but indicated as having a threaded shank 11 fixed in a support such as a car-

riage bow 12. The stud member has a head 13 preferably approximating in form that shown in Fig. 4 having two oppositely arranged shoulders and a width substantially equal to the diameter of the neck 14.

Mating and co-operating with the headed 18 stud is a socket member secured in any suitable manner to the curtain 15 or the like to be attached to the support 12. The socket member comprises a shell 16, the main portion or body of which is substantially cylindrical and provided with an attachment flange 17 having spurs 18 projectable through the curtain and bendable over a ring 19 on the opposite side of the curtain. This manner of attachment of the 20 parts is referred to merely as an illustration of one suitable means and obviously other means may be employed if desired. The curved portion of the shell 16 is provided with a series of grooves or indentations 25 shown as four in number and at 90° apart as in Fig. 3. The face portion of the shell, adjacent to the stud, is provided with a mouth or opening 21 shaped preferably the same as the head 13 and through which the 30 head is designed to pass freely when assembling and disassembling the parts. It is to be understood, however, that there is no relative rotation provided for or desired as between the head and the shell. The head 35 is introduced directly into the shell through the mouth 21 as shown in Fig. 4 and locked in such position by suitable means.

Fixed in the shell, preferably flush with the flange portion 17, is a disk 22 in the 40 center of which is journaled the locking means. In the first set of figures and as shown in detail in Fig. 4^a the locking means comprises a spider having a disk portion 23, a pair of spaced parallel catches 24 on opposite sides of the axis of the locking member and carried by a pair of arms 25 extending from opposite sides of the disk, and a pair of check or detent members 26, likewise carried by arms 27 extending from 45 opposite sides of the disk 23. Each of the arms 25 and 27 is of substantially right angular form with the free end portion thereof extending parallel to the axis of the device. The catches 24, however, lie in 50 the same plane and parallel to the plane of the disk 23, while the detent members at their free ends terminate in a plane coin-

ciding substantially with the plane of the catches. The arms 25 are stronger and stiffer than the arms 27, which latter are in the nature of springs, the same being 5 flexible especially along the intermediate portion or adjacent to the disk. The detents 26 at their ends or points are designed to project outward and snap into the indentations 20 for checking the rotation 10 of the locking member at the quarter turns and holding the same from unintentional rotation in either the open or locked positions. The locking device as a whole may be formed readily as a stamping from 15 a single piece of spring metal. The space between the catches 24 coincides substantially with the width of the head 13 and the diameter of the neck 14 and this will be remembered as being substantially the 20 same as the width of the mouth 21. The length of the catches, however, circumferentially of the device is greater than the width of the mouth so that in the locking position the ends or points of the catches 25 lie or engage beneath the face portion of the shell.

As a suitable means for manipulating the locking member I provide a finger piece 13' which if desired may be in the nature of a 30 head somewhat similar in shape to the head 13 and having a shank or journal portion 28 extending through and journaled in the disk 22 and fixed as by riveting in the center hole of the disk 23. Except for the detents 26 35 the finger piece 13' and the locking member are free to rotate in the disk 22.

The locking member is indicated by dotted lines as occupying its unlocked position in Fig. 4, the detents being seated in the indentations at right angles from the position of the detents in Fig. 3, and the catches 24 being nested beneath the face of the shell at the sides of the mouth 21 so that the head 13 may slip directly and freely into and out of 40 said mouth. After the head is inserted as shown in Fig. 4, the operator rotates the finger piece and locking member through 90°, bringing the same into the position of Fig. 3 at which time the catches 24 engage the 45 shoulder portions of the head and overlap the end portions of the mouth, making a positive interlock between the head and the socket members. In this position it will be understood that the detents, having snapped 50 into the indentations as in Fig. 3, will prevent the accidental rotation and unlocking of the head. The parallel portions of the arms 25 will lie or glide at all times along the inner cylindrical surface of the shell. 55 When the locking member is rotated the detents will ride up out of the indentations beneath the face portion of the shell ready to snap into the next indentations, but it will be noted especially in Fig. 4 that there is 60 sufficient clearance between the head and the 65

cylindrical portion of the shell to permit the rotation of the locking member. In view of the correlation between the head 13 and the mouth portion of the socket member it will be appreciated how important it is for the 70 locking device to be held positively in unlocked position so that the edges of the catches 24 will lie flush with both straight side edges of the mouth, for the head thus will be prevented from engaging beneath the 75 mouth portion of the shell to interfere with free separation of the parts. Moreover, the locking device being left in such position there can never be any obstruction to the re-entry of the head again into the socket at the 80 next operation.

The general characteristics of the form of the device in Figs. 5, 6, and 7 are the same as above described and the several parts of the mechanism, as far as expedient, are similarly numbered. The shell 16' in this form of the invention is provided with a flange 29 extending downward around the mouth 21. This flange is shaped to receive the head 13 and its main purpose is to prevent either rotation of the head or lateral movement thereof in any direction with respect to the socket member or shell. Said flange 29 is provided at its rounded end portions with slots 30 just within or beneath the flat face portion of the shell. From Fig. 7 it will be noted that the flat side portions of the flange 29 terminate at the ends of the slots and so form what may be termed stiff shoulders or 90 detents 31 all arranged in the form of a 100 square and at 90° apart.

The locking device in this form of the invention comprises a pair of catches 24' approximately the same in shape and operation as already described and carried by 105 spring arms 25' from a disk 23 rotated as above described by the finger piece 13' rotating in the disk 22 fixed in the flanged portion of the shell. The catches 24' may be concaved slightly on their free or oppositely arranged edges, but in both the locked and unlocked positions the end portions of the catches bear directly against the 110 detent shoulders 31. The arms 25' being in this form strong springs, serve to cause or 115 compel the locking member to lie positively either in the open unlocked position or in its locked position. Should, therefore, the operator stop rotating the locking member before the complete quarter turn is made the 120 action of the spring arms will automatically complete such rotative action. After the head is introduced into the flanged mouth as shown in Fig. 7 the operator turns the locking member, causing the catches 24' to ride 125 out somewhat around the shoulders 31, clearance being observed at 32 between the parallel portions of the arms 25' and the inner surface of the shell for this purpose, and then the catches will pass into or across the 130

slotted portions of the flange 29 and lie in locked position in said slots as shown in full lines in Figs. 5 and 6, the ends of the catches extending beyond the sides of the head as before described and so making a positive interlock between the parts.

I claim:

1. In a curtain button, the combination with a head and a socket member relatively non-rotatable, the socket member having an opening in one side to receive the head, of a locking member carried by the socket member and including catch means adjacent to the plane of said opening, and means on the side of the socket member remote from the opening and in axial alinement with the head to actuate the catch means for interlocking the head in the socket member.

2. A device as set forth in claim 1 in which the head is oblong and the opening of the socket member is of the same form as the head.

3. In a curtain button, the combination of a socket member comprising a shell of circular form and having a face plate provided with an opening other than circular in form, a head mating and co-operating with the socket member and projectable directly through said opening and conforming substantially thereto, the shell and head being relatively non-rotatable, and means journaled in the center of the side of the socket member remote from the opening and in axial alinement with the head and including catch means surrounding the head within the shell and movable between said plate and the head for interlocking the head in the shell.

4. Mechanism as set forth in claim 3 in which the face plate of the shell comprises a flange entirely surrounding the opening, and the locking member is movable along the inner surface of said flange and cooperates therewith in holding position.

5. In a separable fastener as set forth, the combination with a relatively fixed oblong head and a socket member to receive said head, the socket member including a shell having in one side a mouth conforming to the head and through which mouth the head is projectable directly, of a locking member movable within the shell and comprising a pair of catches spaced on opposite sides of the axis of the head and serving when moved to engage between the end portion of the head and the shell side having the mouth to interlock the head in the socket member, and comprising also a disk lying opposite

the end of the head in a plane parallel to the plane of the catches.

60

6. A device as set forth in claim 5 in which the shell is provided with a face plate in which the aforesaid mouth is formed, the face plate surrounding the mouth constituting a circular flange beneath which the catches of the locking member co-operate.

65

7. In a separable fastener as set forth, the combination with a relatively fixed non-circular head and a socket member including a relatively stationary shell having a mouth of the same form as the head and through which mouth the head is projected, of a locking member comprising a disk journaled in the shell directly opposite and adjacent to the head, for rotation around the axis of the head and comprising also catch means lying in a plane remote from the disk and on the opposite side of the head therefrom and movable during such rotation into interlocking position between the head and the part 75 of the shell having the mouth.

70

8. A device as set forth in claim 7 in which the locking means comprises a plurality of catch members and arms for the catch members extending parallel to the axis of 80 the head around the edge portion of the head.

85

9. The herein described curtain button comprising a head having shoulders, a socket member having an opening in one side to receive said head directly therethrough, the head and socket member being relatively non-rotatable, catch means rotatable within the socket member and around the head, said catch means comprising a spider having a 90 pair of catch members operating in a plane close to the side of the socket member having the opening and engageable beneath said shoulders, a disk adjacent to the end of the head in a plane parallel to the plane of the 100 catch members, and a pair of arms extending from the disk parallel to the axis of the head and carrying said catch members, and means connected to the catch means to rotate the same into locking or unlocking position.

95

10. Mechanism as set forth in claim 9 in which the spider includes spring detent means carried by the disk and approximately parallel to the axis of the head while the socket member is provided with depressions into which the detent means is engageable while moving radially outward from the axis of the head.

105

110

In testimony whereof I affix my signature.

ROBERT A. MOORE.
